UNITED STATES PATENT OFFICE

WILLIS L. LYNDE, OF WEST BEND, WISCONSIN, ASSIGNOR OF ONE-HALF TO VICTOR GEIB, OF WEST BEND, WISCONSIN

DESIGN FOR A PAINT BRUSH

Application filed July 19, 1930. Serial No. 36,401. Term of patent 14 years.

To all whom it may concern:

Be it known that I, WILLIS L. LYNDE, a citizen of the United States, and a resident of the city of West Bend, in the county of Washington and State of Wisconsin, have invented a new and ornamental Design for a Paint Brush, of which the following is a specification, reference being had to the accompanying drawings, forming a part thereof.

Fig. 1 is a perspective view of a paint brush, showing my new design; and Fig. 2 is a side view of the same.

I claim:

The ornamental design for a paint brush, as shown.

In testimony whereof, I have signed my name at Milwaukee, this 7th day of July, 1930.

W. L. LYNDE.
